UNITED STATES PATENT OFFICE.

FLORENTIN KASANTZEFF, OF BERLIN, GERMANY.

ONE-LINED AIR BRAKE.

Application filed July 21, 1926. Serial No. 124,031.

The invention relates to a special device and arrangement of parts in an air brake of the type having only one air pipe running along the railway train or other cars to be braked.

The essential feature consists in a ruling device, which on a decrease or increase of pressure, produced in the train pipe, produces a stronger decrease or increase of air pressure in a governing chamber of the distributor, used for feeding air to and exhausting it from the brake cylinder. Hereby a specially precise governing of the brake action is attained. Further, the ruling device may be advantageously so constructed, that it produces inverse pressure alterations as induced in the train pipe, and an extraordinary simple and effective distributor is used in connection therewith.

20 A sample of the invention is shown in the drawing, in which the ruling device and distributor are shown in section.

On the locomotive or other tractor the usual appliances may be arranged, such as an air pump, a main air container and a leader's valve, which serve for producing and maintaining any desired pressure in the train pipe 4 running along the cars or wagons to be braked.

30 On a wagon, a feed valve 5 is connected to the train pipe 4 and a pipe 11 leads from said feed valve to a chamber 37 of the distributor 8', which in its turn is connected to the auxiliary container 6 by a pipe 10' and to the brake cylinder 9. A ruling device 7' is connected to the train pipe by a pipe 50, further to the auxiliary container 6 by a pipe 51, and to the governing chamber 52 of the distributor 8' by a pipe 12.

40 The ruling device 7' contains two diaphragms 27 and 28 of different sizes and a loading spring 30' is so arranged as to press the larger diaphragm 27 inward. The space 53 between the diaphragms is connected to the train pipe 4. The space 54 below the larger diaphragm 27 is connected to the atmosphere, and the space 55 above the smaller diaphragm 28 is connected to the above mentioned pipe 12. A double valve 56 is so arranged, that it connects the space 55 alternately to the atmosphere or to a chamber 57, which communicates with the pipe 51 leading to the auxiliary container 6 and to the distributor.

55 The action is as follows. When a certain

normal pressure exists in the middle chamber 53, atmospheric pressure exists in the upper chamber 55. When the pressure in chamber 53 becomes augmented or diminished, in consequence of the different areas of the diaphragms and due to the spring 30', corresponding pressure differences in an increased degree and in inverse sense are produced in the upper chamber 55 by aid 60 of the double valve 56.

In the appertaining distributor 8' three diaphragms 38, 39, 40, an air chamber 37 and a double valve 47 are arranged as shown in the drawing. The chamber 58 between the greatest diaphragms 38, 39 is open to the atmosphere. The chamber 59 between the smaller diaphragms 39, 40 is connected to a valve cone 60, which has an atmospheric channel 61 and a connecting channel 62 70 adapted for connecting the space 59 to the smaller chamber 63 and to the brake cylinder 9.

The general action of the whole device is that in running position all chambers of the distributor are under atmospheric pressure, but any decrease of pressure in the train pipe 4 produces an increase of pressure in the distributor chamber 52, and thereby the diaphragm system is moved toward the chamber 37 and admits air from the said chamber through the valve 47 to the diaphragm 40 to such an extent, that the air pressure thus produced, which pressure also acts in the brake cylinder, balances the air pressure in the governing chamber 52. Inversely an increase of air pressure in the train pipe 4 produces a decrease of pressure in said chamber 52 and thereby an inverse movement of the diaphragm system, so that through the double valve 47 air is exhausted from chamber 63 and the brake correspondingly released.

100 In the shown position of the valve cone 60 a strong braking action is obtained, as needed for loaded wagons, as follows. The intermediate chambers 58 and 59 being open to the atmosphere, the whole area difference of the greatest diaphragm 38 and the smallest diaphragm 40 is effective for the movement of the diaphragm system, and therefore strong pressure difference and corresponding strong braking actions are produced by the chamber 63. When the valve cone 60 is 105 turned so as to connect the spaces 59 and 63, a weaker braking action is obtained due to

the smaller difference of area of the now acting diaphragms 38 and 39; this position is used for unloading wagons. In each case the double valve 47 has the action of admitting or exhausting air to or from the chamber 63 and the brake cylinder, so that graduated braking or brake loosening according to the pressures produced in the chamber 52 is obtained.

10 It is to be remarked that any overnormal pressure arising in the train pipe can not disturb the brake, as it has only the effect of compressing the spring 30' opening thereby more or less by valve 56 the atmospheric 15 outlet of the chamber 55 which in normal running position has to be under atmospheric pressure.

Further, due to the circumstance, that all 20 chambers of the distributor are under atmospheric pressure in running position, extremely small losses of air are encountered, and any braking action becomes very precise, as the pressure graduations in the governing 25 chamber 52 of the distributor, arising on the base of atmospheric pressure, are relatively great and thereby very effective.

The air chamber 37 acts as an advantageous acceleration chamber by quickly furnishing a certain quantity of air for applying the brake blocks to the wheels, and moreover it smoothes the variations of the braking pressures.

I claim:

1. A one lined air brake comprising in 35 combination a train pipe, an auxiliary air container, a brake cylinder, a distributor adapted to admit air from said auxiliary container to said brake cylinder, and a ruling device so connected to said train pipe and 40 distributor, that by different pressures in said train pipe, below a normal running pressure, relatively greater pressure differences are produced in the connection to said distributor.

45 2. A one lined air brake comprising in combination a train pipe, an auxiliary air container, a brake cylinder, a distributor adapted to admit air from said auxiliary 50 container and train pipe to said brake cylinder, and a ruling device so connected to

said train pipe and distributor, that by different pressures in said train pipe, below a normal running pressure, relatively greater pressure differences are produced in the connection to said distributor.

55

3. A one lined air brake comprising in combination a train pipe, an auxiliary air container, a brake cylinder, a distributor adapted to admit air from said auxiliary container to said brake cylinder, and a ruling device so connected to said train pipe and distributor, that by different pressures in said train pipe, below a normal running pressure, inversely corresponding pressure variations are produced in the connection to said distributor.

60

4. A one lined air brake comprising in combination a train pipe, an auxiliary air container, a brake cylinder, a distributor adapted to admit air from said auxiliary 70 container to said brake cylinder, and a ruling device comprising two piston like acting members of different areas, operatively connected to each other, an atmospheric chamber adjoining to the outer face of the larger 75 of said members, a chamber between said members, connected to the train pipe, a second chamber adjoining to the outer face of the smaller of said member and connected to the distributor, a spring pressing said greater member inward, and a double valve in operative connection to said members, so that on an increase of pressure in said middle chamber an increase of pressure in said second chamber is produced.

85

5. A one lined air brake comprising in combination a train pipe, an auxiliary air container, a brake cylinder, a ruling device adapted to produce positive air pressure corresponding to train pipe air pressure 90 diminutions, and a distributor containing two piston like acting members of different areas, the greater of which members being loaded by the air pressure produced by said ruling device, and the smaller of which being loaded in opposite direction by the air contained in the brake cylinder.

95

In witness whereof I affix my signature.

FLORENTIN KASANTZEFF.
